(57) **CLAIM**

The ornamental design for a wrench handle, as shown and described.

DESCRIPTION

FIG. 1 is a top front perspective view of a wrench handle showing my new design;

FIG. 2 is front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a top view thereof, attached with an example adjustable wrench head;

FIG. 9 is a right side elevation view thereof, attached with the same example adjustable wrench head shown in FIG. 8;

FIG. 10 is a rear elevation view thereof, attached with the same example adjustable wrench head shown in FIGS. 8 and 9;

FIG. 11 is a top view thereof, attached with the same example adjustable wrench head shown in FIGS. 8, 9, and 10, but with the example adjustable wrench head rotated 180 degrees;

FIG. 12 is a right side elevation view thereof, attached with the same example adjustable wrench head shown in FIGS. 8, 9, and 10, but with the example adjustable wrench head rotated 180 degrees as shown in FIG. 11; and,

FIG. 13 is a rear elevation view thereof, attached with the same example adjustable wrench head shown in FIGS. 8, 9, and 10, but with the example adjustable wrench head rotated 180 degrees as shown in FIGS. 11 and 12.

The broken lines shown in FIGS. 8-13 show unclaimed subject matter only and form no part of the claimed design.
